UNITED STATES PATENT OFFICE.

MARJORIE F. SMITH, OF REDLANDS, CALIFORNIA.

DETACHABLE BED-GUARD.

1,062,127.

Specification of Letters Patent.

Patented May 20, 1913.

Application filed October 17, 1910. Serial No. 587,376.

To all whom it may concern:

Be it known that I, MARJORIE F. SMITH, a citizen of the United States, residing at Redlands, in the county of San Bernardino, State of California, have invented new and useful Improvements in Detachable Bed-Guards, of which the following is a specification.

This invention relates to bed steeds, and 10 the object of the invention is to produce a portable attachment which can be secured to the side of a bed steed so as to form a bar or guard on the side thereof to prevent an infant from falling out of the bed. Where 15 one side of the bed steed is barred by a wall it is only necessary to provide one of these devices.

The device is constructed of flexible members which can be rolled up and readily carried from place to place or packed in a 20 trunk or a shipping case.

The invention resides also in the combination of means for securing the ends of the device to the bed steed, and to means for 25 taking up the slack where the device is too long for the bedstead.

In the drawing forming a part of the annexed specification, Figure 1 is a perspective showing the bed steed and showing a corner of the room in which the bed steed is placed, and illustrating the manner in which my device is applied to the outer side of the bedstead. Fig. 2 is a side elevation showing one of the devices removed 35 from the bedstead, and showing the same broken away. Fig. 3 is a perspective of a snap hook which constitutes a feature of the invention. Fig. 4 is a horizontal section taken through the foot board of a bed steed 40 and showing the means employed for securing the device to the corner posts when the corner post is constructed so as to prevent the fastening from being passed completely around it. Fig. 5 is a side elevation showing 45 one end of the take-up devices when having the construction shown in Fig. 4, and this view also illustrates take up devices for taking up the slack of the device to make it hang in a taut condition between the corner 50 posts where it is applied. Fig. 6 is a plan or upper edge elevation showing one of the take up devices and the manner in which it operates to take up the slack as suggested. Fig. 7 is an end elevation of the device 55 showing the same rolled up ready for transportation or packing away.

Referring more particularly to the parts, 8 represents the bedstead of any suitable construction, and made of iron or brass or similar metal. This bed steed has a foot 60 frame 9 with corner posts or foot posts 10 and a head frame 11 having corner posts or head posts 12. The bedstead illustrated is represented as placed in the corner of the room so that it is closed on its inner side by 65 a wall.

In order to adapt the bed steed to prevent an infant from falling out of it I provide the outer side of the bed steed with one of my bars or guards 13 and this guard has 70 two longitudinally disposed strips 14 of leather or similar flexible material; and between these two strips 14 intermediate strips 15 are provided, all of said strips extending parallel with each other and being connected together by vertical bars or slats 16. At one end the strips 14 are extended so as to form tapered tongues 17 to the ends of which snap hooks 18 are attached, and these snap hooks are adapted to be placed 80 around the foot post 10 and attached to rings 19 secured on the sides of the straps as shown. At the opposite end of the guard I provide straps 20 which are adapted to pass around the head post and can be secured thereto by means of buckles 21 attached to strips as indicated. The lower strip 14 is provided with two light straps or strings 22 which are adapted to be tied around the outer side rail 23 of the bed- 90 stead. This gives the guard additional security near its middle point.

At a suitable point on the strips 14 I provide take up straps 22, coöoperating with buckles 23 which enable the slack of the 95 strips to be taken up if the guard is too long for the bedstead to be drawn taut by the end fastening devices. The manner in which this take up device is operated is indicated in Fig. 6, which view represents the strips 14 at the point where the slack has been taken up, the surplus of the material of the strips 14 being disposed in loops 24 as shown.

The device may be used on bedsteads which do not present round posts similar to the posts 10 and 12 and in order to adapt it for use in such a case I provide the construction shown in Fig. 5. In this view the upper and lower strips 25 are not extended beyond the ends of the guard but are provided with 110 flexible metal hooks 26 which are adapted to bend around the outer side of the corner post

as shown in Fig. 4. The inner ends of these hooks are pivotally attached by eyelets 28 to the ends of the strips as shown. It should be understood that these hooks 26 have sufficient stiffness to retain the position into which they are bent at the post 27, the ends of the hooks passing around and coming against the outer face of the headboard 29 or foot board as indicated. In other respects 10 the guard is constructed identically with the guard shown in Fig. 2 having take-up devices 30 on the strips 25 and having intermediate strips 31, all the strips being connected by vertical slats 32 as shown.

15 The bed guard constructed as described can be rolled up into a roll as indicated in Fig. 7 when not in use and in this form may be conveniently carried or packed in a trunk for traveling. It can be readily applied as 20 an attachment for the sides of bedsteads or berths, operating to prevent an infant from rolling out of the bed as suggested above. When the device is in daily use the straps 20 may be left permanently secured and the 25 snap hooks released to permit the guard to be folded back.

What I claim is:—

1. A bed guard consisting of a pair of longitudinally disposed flexible strips, straps 30 and buckles attached at the inner end of said strips for securing the same to a bed post, detachable snap hook devices at the op-

posite ends of said strips adapted to secure the same to the opposite bed post, intermediate strips disposed between said first strips, 35 transverse rigid slats connecting all of said strips, takeup devices disposed on said first strips for taking up the slack thereof, and means on said guard for securing the same at an intermediate point to the side rail of 40 the bedstead.

2. A bed guard consisting of upper and lower longitudinally disposed flexible strips, straps and buckles attached at one end of said strips for securing the same to a bed 45 post, detachable snap hook devices at the opposite ends of said strips adapted to secure the same to the opposite bed post, intermediate strips disposed between said first strips and lying in the same plane as the 50 said upper and lower strips, means mounted on said flexible strips to adjust the length of said bed guard and transverse rigid slats connecting all of said strips whereby the longitudinally disposed flexible strips are 55 prevented from sagging when the guard is attached to a bed.

In witness that I claim the foregoing I have hereunto subscribed my name this 7th day of October, 1910.

MARJORIE F. SMITH.
